(57) **CLAIM**

We claim the ornamental design for a grill scraper, as shown and described.

DESCRIPTION

FIG. 1 is a top, front, right side perspective view of a grill scraper showing our new design;

FIG. 2 is a bottom, rear, left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the figures represent portions of the grill scraper that form no part of the claimed design. In the figures, the handle has been broken to indicate indefinite length.
